UNITED STATES PATENT OFFICE

2,549,664

ELEVATING MECHANISM AND BRAKE
CONTROL FOR REFRIGERATOR SHELF
FRAMES

Douglas Collins, Salisbury, N. C.

Application April 6, 1945, Serial No. 586,899

18 Claims. (Cl. 312—223)

1

The higher efficiency and operational advantages of refrigerators of the type in which access to the refrigerating chambers is obtained from above through a top door over those in which access is afforded through a vertically disposed front door is well recognized by those familiar with the construction and design of such equipment.

However the difficulties encountered in fulfilling the requirements of ease and convenience in gaining access to the supporting shelves particularly of domestic household refrigerators has so far retarded adoption of the top door type.

The object of the present invention is to solve these problems by providing a refrigerator embodying vertically movable shelf frames which are automatically moved to a position elevated above the refrigerating chambers under control of manually operated brake members, such movement being utilized to open the top door and thereby afford full access to all articles supported upon the shelves.

A further object is the provision of means for manually regulating the lifting force applied to the shelf frames in dependence upon the nature and the weight of the articles supported thereon.

A still further object is to utilize a part of the energy delivered by the shelf elevating the motor to withdraw air from a chamber formed within the cabinet walls to improve the heat insulating qualities thereof and also to economize in the weight and the cost of the cabinet structure.

With these and other objects in view as will be apparent from the following description, the invention is illustrated in the accompanying drawings in which:

Figure 1 is a perspective view of the improved refrigerator illustrating one of the shelf frames in elevated position.

Figure 2 is a detail perspective view partly broken away of one of the shelf frames and related parts removed from the cabinet.

Figure 3 is a detail view of the interior of one corner of the cabinet showing the guide roller for one of the corner posts of the shelf frame.

Figure 4 is a detail vertical sectional view through the cabinet showing a guide pulley for one of the shelf frame elevating cables.

Figure 5 is a detail horizontal sectional view through a corner of the cabinet illustrating the upper pulley for guiding the elevating cable.

Figure 6 is a detail sectional view through the cabinet illustrating the brake controlling one of the shelf frames.

2

Figure 7 is a detail view through the lower portion of one of the corner posts of the shelf frame illustrating the manner in which the elevating cable is attached thereto.

Figure 8 is an enlarged detailed sectional view of the spring motor for elevating the shelf frame.

Figure 9 is a longitudinal sectional view through the device for moving the top door to closed position.

Figure 10 is a vertical sectional view through the pump operated by the shelf frame.

Figure 11 is a detail sectional view on an enlarged scale showing the upper part of the pump.

Figure 12 is a detail sectional view of the pump illustrating the sealing device therefor.

Referring to the drawings in detail, the numeral 15 designates the refrigerator cabinet which is provided at the bottom with lateral drawers 16 and a central bottom chamber 17 for accommodating the freezing unit. The cabinet 15 is open at the top to afford access thereto and in the embodiment of the invention illustrated two chambers for refrigerating purposes are provided and one central chamber for frozen food. Doors 18

25 for closing the open tops of the refrigerating chambers are hinged at their rear ends to the rear wall of the cabinet 15 and the refrigerating chambers are preferably provided with window openings in which transparent panels 19 of some such material as Lucite are arranged.

A shelf frame designated generally at 20 is disposed within each of the refrigerating chambers and consists of vertical corner posts 21 secured in position by frame-like shelves 22, the 35 shelves and posts being sealed or otherwise rigidly connected to form a unitary structure. Pulleys 23 mounted in brackets 23a attached to the cabinet walls are arranged in the four corners of each refrigerating chamber at points

40 spaced below the open top and these pulleys enter slots 24 formed longitudinally in the posts 21 for the purpose of guiding the vertical movement of each shelf frame and also to provide guides for the four elevating cables 25 associated with the shelf frame. Guide rollers 26 mounted in brackets 26a attached to the cabinet walls are arranged at the corners of each chamber above the pulleys 23 and are provided with grooved surfaces engaging the corner posts 21

45 to further assist in guiding the vertical movement of each shelf frame.

One end of each group of cables 25 is secured at 27 to the lower ends of the corner posts 21 as shown in Figure 7 and passing upwardly 50 through these hollow posts the cables are trained

over the pulleys 23 and extend downwardly along the corners of the refrigerating chamber and over a second group of pulleys 28 located at the bottom of the chamber. The cables 25 extend inwardly from the pulleys 28 toward the center of the refrigerating chamber and each is wound upon and terminally attached to a drum 29.

The drum 29 constitutes part of the motor for elevating each shelf frame and as shown in Figure 8 the drum is mounted upon a shaft 30 secured by a bracket 31 to the central portion of the bottom of the refrigerating chamber. A coil spring 32 is housed within the drum 29 and one end is attached at 33 to the drum. The opposite end of the spring is secured at 34 to the shaft 39 on which the drum 29 is rotatably mounted and a worm wheel 35 is keyed to the shaft 30 and constitutes part of the mechanism for regulating the tension of the spring. As will be understood the tension of the spring is so applied to the drum 29 as to normally tend to turn the latter in the direction for winding the cables 25 thereon so that a lifting force is applied to each of the four corners of the shelf frame through the cables which tends to move said shelf frames to elevated position.

By rotating the worm wheel 35 the tension of the spring 32 may be varied and thus the force tending to elevate the shelf frame may be regulated as required in accordance with the weight and nature of the articles supported thereon. The teeth of the worm wheel 35 are engaged with a worm 36, the pitch of which is so chosen as to provide a non-reversible drive, that is to say, the rotary movement of the worm 36 may be imparted to the wheel 35 but the torque applied to the wheel by the spring is incapable of revolving the worm.

The worm 36 within each chamber is connected by a flexible shaft 37 with a manually operable hand crank 38 located externally of the cabinet 15 within convenient reach and by manipulation of the crank in one direction or the other the lifting force applied to each shelf frame may be varied as desired.

Each shelf frame is normally prevented from moving upwardly under the influence of the spring motor by a friction brake member 39 engaged with one of the corner posts 21 and secured to a lever 40 pivotally mounted at 41 at a suitable point on the wall of the cabinet 15. The brake member 39 is normally held in engagement with the corner post by a spring 42 and the pivotal mounting 41 of the lever is so disposed with respect to the brake member and the corner post that the upward movement of the shelf frame tends to increase the braking effect of the brake member and thereby arrest the ascending movement of the frame. The lever 40 is connected with a rod 43 projecting externally of the cabinet and connected with a button 44 for convenience in releasing the brake and permitting the shelf frame to rise to the desired position.

The rear part of the shelf frame is provided with a pair of rollers 45 engaging the under side of the door 18 whereby the latter is moved to open position during the upward movement of the shelf frame.

To increase the heat insulating properties of the cabinet the portions thereof are all of double wall cellular construction forming a fluid tight internal chamber from which the air is withdrawn by the pump illustrated in detail in Figures 10 and 11. The pump for creating and

maintaining a partial vacuum in the wall chambers 47 consists of a hollow piston 48 secured at 49 to the bottom of the cabinet 15 and a cylinder 50 secured at 51 to and moving with the shelf frame. The lower end of the cylinder is flanged and provided with sealing means 52 to form a fluid tight joint with the piston.

A sealing valve 53 is arranged in the upper end of the hollow piston 48 and is normally maintained in engagement with the seat 54 by a spring 55 confined by a retaining member 56. The purpose of the sealing valve 53 is to maintain the sub-atmospheric pressure in the chamber 47 and prevent the admission of air at atmospheric pressure. A valve 57 for limiting the reduction of pressure in the chamber 47 is arranged in the top of the cylinder 50 and is normally retained in engagement with a seat 58 by a spring 59. Additional ports 60 are formed in the valve seat 58 and are controlled by a gravity actuated check valve 61 permitting the escape of air from the cylinder 50 as the shelf frame is lowered. The cylinder 50 is secured at 62 to the member 51 by which the pump is attached to the shelf frame and an air port 63 is provided in the member 51.

For convenience in manually lowering each shelf frame and restoring the latter to its position within the refrigerating chamber, the top member of the shelf frame is formed with a forwardly and downwardly projecting portion 65 which, as shown in Figure 1, is located externally of the cabinet when the doors 18 are closed.

Upon operation of one of the buttons 44 and release of the brake member 39 the related shelf frame 20 is moved upwardly by the cables 25 actuated by the spring motor driven drum 29.

During its ascending movement the shelf frame swings the door 18 to open position through the rollers 45 and the shelf frame continues to rise 40 until the movement thereof is arrested by the brake member 39 upon release of the button 44. During the first stage of the upward movement of the shelf frame, the reduction in pressure in the cylinder 50 tends to withdraw air from the insulating chamber 47, the valve 53 opening and the valve 57 remaining closed under the influence of the spring 59. When the pressure is reduced to a predetermined value the tension of the spring 59 is overcome and the valve 57 opens admitting air to the space between the valves 53 and 57. It will be understood, however, that the valve 53 closes instantaneously thereby preventing the admission of air at atmospheric pressure to the chamber 47. During the subsequent upward movement of the shelf frame the valve 53 remains closed and the slow admission of air to the cylinder under control of the spring actuated valve 57 acts to check or retard upward movement of the shelf frame. Further means such as designated

at 65 in Figure 1 and illustrated in detail in Figure 10 may be used in conjunction with the vacuum pump or in substitution thereof in case the pump is not desired for yieldably retarding the upward movement of the shelf frame. This retarding device consists of a cylinder 66 secured at 67 to the cabinet 15 and a piston rod 68 secured at 69 to the top 18. A piston 70 secured to the rod 68 is moved in the cylinder under the influence of a spring 71. The tension of the spring 71 tends to maintain the door 18 in engagement with the rollers 45 but during opening movement of the door under the influence of the elevating motor the spring 71 is compressed but the slow escape of air through a port 72 in the cylinder retards the opening of the door 18

70

to the extent desired. During the closing movement of the door 18 a valve 73 opens to freely admit air to the cylinder 66.

What is claimed is:

1. In a refrigerator, a cabinet having an open top refrigerating chamber, a door for the open top, a shelf frame vertically movable in said chamber, means constantly exerting a force sufficient to elevate the frame when loaded, self-energizing brake means for yieldably retarding movement of the frame including a pivotally mounted brake shoe normally but releasably engaged with a portion of said frame and effective in all vertical positions of said frame to arrest upward movement thereof and with the distance from the point of pivot of the shoe to the arc described by the lower portion thereof being greater than the distance from the point of pivot to the portion of the frame engaged by the shoe whereby upon any force moving the frame upwardly the shoe is moved upwardly into jamming engagement with the frame to frictionally engage the frame and prevent upward movement thereof, and means arranged externally of said cabinet for controlling the brake means.

2. In a refrigerator, a cabinet having an open top refrigerating chamber, a door for the open top, a shelf frame vertically movable in said chamber, means constantly exerting a force sufficient to elevate the frame when loaded, and manually releasable brake means normally effective in all vertical positions of said frame to arrest movement of the frame in selected positions.

3. In a refrigerator, a cabinet having an open top refrigerating chamber, a door for the open top including marginal edge walls, a shelf frame vertically movable in said chamber, means constantly exerting a force sufficient to elevate the frame when loaded, manually operable means to releasably arrest movement of the frame in selected positions, and a handle on the top of said frame projecting outwardly therefrom and terminating in spaced relation to the frame a distance such that the handle projects beyond one of said edge walls of the door and said handle further having such dimensions as to extend externally of said cabinet when the door is closed on top of the frame.

4. In a refrigerator, a cabinet having an open top refrigerating chamber, a door for the open top, a shelf frame vertically movable in said chamber, means constantly exerting a force sufficient to elevate the frame when loaded, a manually operable member arranged externally of said cabinet, and means controlled by the member for regulating the force exerted by said force exerting means.

5. In a refrigerator, a cabinet having an open top refrigerating chamber, a pivotally mounted door for the open top, a shelf frame vertically movable in said chamber, means constantly exerting a force sufficient to elevate the frame when loaded, means carried by the frame and cooperative with said door for swinging said door to open position during elevation of said frame, self-energizing brake mechanism normally engageable with said frame to arrest upward movement thereof, means for releasing the brake mechanism to permit elevation of the frame to selected positions and means normally tending to close said door.

6. In a refrigerator, a cabinet having an open top refrigerating chamber, a shelf frame vertically movable in said chamber, spring means

constantly exerting a force sufficient to elevate the frame when loaded, and manually operable means for regulating the tension of the spring means to correspond with the load on said shelf frame.

7. In a refrigerator, a cabinet having an open top refrigerating chamber, a shelf frame vertically movable in said chamber, a spring motor, means actuated by said motor to elevate said frame, brake means normally effective in all vertical positions of said frame to arrest movement of said frame, and manually operable means to render the brake means ineffective whereby the shelf frame may be moved to the desired elevation by said motor.

8. In a refrigerator, a cabinet having an open top refrigerating chamber, a shelf frame movable vertically in said chamber, and including slotted corner posts and rotatable guide members secured to the cabinet and partially engaged in the post slots.

9. In a refrigerator, a cabinet having an open top refrigerating chamber, a shelf frame movable vertically in said chamber and including slotted corner posts, and rotatable guide members mounted on the cabinet and partially engaged in the post slots, actuating cables attached at one end to the posts, extending upwardly therein over the guide members and downwardly in the corners of the chamber.

10. A refrigerator as claimed in claim 9 provided with a motor, and a drum driven by said motor to which the opposite ends of the cables are attached.

11. In a refrigerator, a cabinet having walls forming an open top refrigerating chamber, said walls being hollow to form an internal chamber, a shelf frame vertically movable in the refrigerating chamber, force applying means tending to elevate said frame, and a pump operable by the upward movement of the frame to withdraw air from said internal chamber.

12. A refrigerator as claimed in claim 11 wherein said pump includes piston and cylinder elements, a valve preventing admission of air to the internal chamber, and means connecting the respective elements with the cabinet and frame.

13. A refrigerator as claimed in claim 11 wherein said pump includes a valve for determining the reduction in pressure in said internal chamber and operative when said pressure reaches a predetermined value to yieldably retard upward movement of said frame.

14. A refrigerator as claimed in claim 11 wherein said pump includes a hollow piston communicating with said internal chamber, a cylinder coacting with said piston, and valve means for determining the reduction in pressure in said internal chamber produced by operation of said pump.

15. A refrigerator as claimed in claim 11 wherein said pump includes a hollow piston connected to said cabinet and communicating with said internal chamber, a cylinder connected to said shelf frame and coacting with said piston, valve means for determining the reduction in pressure in said internal chamber produced by operation of said pump, said pump being operative during the initial upward movement of the frame to withdraw air from the internal chamber, and said valve means being operative during the succeeding movement of the frame to yieldably retard said movement.

16. In a refrigerator, a cabinet having an open top refrigerating chamber, a shelf frame includ-

ing vertical corner posts vertically movable through the open top of said chamber, a hinged door engaged and swung by said frame to open position during the upward movement of said frame, means operative to close said door, means ¹⁵ acting in opposition to said closing means and operative to elevate said frame, and manually operable means for releasably arresting movement of the frame in selected vertical positions including a self-energizing brake mechanism normally frictionally engaging one of said posts and effective in all vertical positions of the frame to arrest upward movement thereof and releasable means controlling the brake and effective upon operation to release the brake to permit elevation of said frame to selected positions.

17. In a refrigerator, a cabinet having an open top refrigerating chamber, a door for the open top, a shelf frame vertically movable in said chamber, adjustable means constantly exerting a force sufficient to elevate the frame when loaded, manually settable means for adjusting the elevating means to vary the elevating force exerted on said frame, stop means normally effective to prevent upward movement of the frame, and release means operative to render the stop means ineffective whereby the frame may be elevated to a selected position by the force exerting means, the frame being stopped in the selected position by the stop means under control of the release means.

18. A shelf construction including in combination a movable shelf frame means constantly applying force to said frame to translate the same from its original position, a releasable self-energizing brake mechanism normally frictionally engaging a portion of said frame in opposition to said force applying means to prevent movement

of said frame and control means for said brake mechanism effective upon operation to release the braking action to permit movement of said frame as long as the braking action is released and said brake means being operative upon cessation of operation of said control means to substantially immediately arrest movement of said frame.
